UNITED STATES PATENT OFFICE.

WILLIAM I. BUNKER, OF CHICAGO, ILLINOIS.

DESIGN FOR A BRACKET.

SPECIFICATION forming part of Design No. 16,541, dated February 23, 1886.

Application filed January 19, 1886. Serial No. 189,110. Term of patent 14 years.

To all whom it may concern:

Be it known that I, WILLIAM I. BUNKER, a citizen of the United States, residing at Chicago, in the county of Cook and State of Illinois, have invented and produced a new 5 Design for Brackets, of which the following is a specification.

The leading feature of my design is a bracket presenting in outline the form or configuration 10 of a conventionalized capital letter E, and I have illustrated this design in the accompanying drawing.

In illustrating a bracket embodying my design and presenting the outlines of a conventionalized capital letter E, I have shown a 15 back or main piece, A, and two end portions, B, and a middle portion, C, all projecting from one side of and substantially at right

angles to the main piece. The ends of the main piece may be somewhat farther apart 20 than the outside edges of the projecting portions B. This main piece and its three projecting portions, all extending therefrom in the same direction, present the design.

I claim—

A design for brackets presenting the shape 25 or configuration of a conventionalized capital letter E, as shown and described, comprising a main piece, two end pieces, and one middle piece projecting therefrom in the same direction, substantially as described.

WILLIAM I. BUNKER.
